UNITED STATES PATENT OFFICE.

JOHN DRAYCOTT, OF PAWTUCKET, RHODE ISLAND, ASSIGNOR TO RICHMOND LACE WORKS, OF ALTON, RHODE ISLAND, A CORPORATION OF MAINE.

DESIGN FOR LACE.

60,935.

Specification for Design.

Patented May 9, 1922.

Application filed January 30, 1922. Serial No. 446. Term of patent 3½ years.

To all whom it may concern:

Be it known that I, JOHN DRAYCOTT, a citizen of the United States, residing at Pawtucket, in the county of Providence and State of Rhode Island, have invented a new, original, and ornamental Design for Lace, of which the following is a specification, reference being had to the accompanying drawing, forming part thereof.

The figure is a face view of lace showing my new design.

I claim:—

The ornamental design for lace, as shown.

JOHN DRAYCOTT.
